FOREIGN PATENT DOCUMENTS

DE 4005647 A1 8/1990

Primary Examiner — Patricia Palasik*(74) Attorney, Agent, or Firm* — Middleton Reutlinger; James E. Cole(57) **CLAIM**

The ornamental design for a cutting tool, as shown and described.

DESCRIPTION

FIG. 1 is a lower front perspective view of the cutting tool design;

FIG. 2 is an upper rear perspective view of the cutting tool design of FIG. 1;

FIG. 3 is a front view of the cutting tool design of FIG. 1 wherein the rear view is a mirror image and is not included; FIG. 4 is a left side view of the cutting tool design of FIG. 1 wherein the right side view is a mirror image and is not included;

FIG. 5 is a top view of the cutting tool design of FIG. 1; and, FIG. 6 is a bottom view of the cutting tool design of FIG. 1. The broken lines showing environmental structure are for illustrative purposes only and form no part of the claimed design.
